UNITED STATES PATENT OFFICE

142,909

DESIGN FOR AN INFANT'S PORTABLE TOILET SEAT

Sacha S. Schnittmann, St. Louis, Mo.

Application November 6, 1944, Serial No. 116,184

Term of patent 14 years

(Cl. D4—5)

To all whom it may concern:

Be it known that I, Sacha S. Schnittmann, a citizen of the United States and a resident of St. Louis, Missouri, have invented a new, original, and ornamental Design for Infant's Portable Toilet Seat, of which the followingg is a specification, reference being had to the accompanying drawings, forming part thereof, in which

Fig. 1 is a top plan view of my new design for infant's portable toilet seat;

Fig. 2 is a side elevation;

Fig. 3 is a front elevation;

Fig. 4 is a perspective oblique front view; and,
Fig. 5 is a perspective side view opposite to the side view shown in Fig. 2.

The dominant features of the design reside in the seat, substantially as shown in full lines, surrounded by an animal head, substantially as shown.

I claim:

The ornamental design for an infant's portable toilet seat, substantially as shown and described.

SACHA S. SCHNITTSMANN.
